UNITED STATES PATENT OFFICE.

CHARLES J. SCHIEMER, OF MOUNT JOY, PENNSYLVANIA.

NUTCRACKER.

1,318,182.

Specification of Letters Patent.

Patented Oct. 7, 1919.

Application filed January 3, 1918, Serial No. 210,131. Renewed September 4, 1919. Serial No. 321,656.

To all whom it may concern:

Be it known that I, CHARLES J. SCHIEMER, a citizen of the United States of America, and a resident of Mount Joy, county of 5 Lancaster, and State of Pennsylvania, have invented certain new and useful Improvements in Nutcrackers, of which the following is a full and clear specification.

The object of this invention is to provide 10 a simple nut-cracker of the hand-lever type, and it consists of certain novel features of construction hereinafter described and claimed.

In the drawing:—

15 Figure 1 is a perspective view showing the position in which pressure is applied to the nut;

Fig. 2 is a vertical sectional view thereof; and

20 Fig. 3 is a detail horizontal view taken through the eccentric cam devices.

In the drawing, *a* designates a standard provided with a suitable clamp at its lower end to enable the standard to be attached to 25 a suitable support. At the upper end of the standard is cast integral a stationary upright jaw *b* whose nut-engaging surface faces laterally with respect to the standard and is provided with serrations. Formed 30 integral with the jaw *b* and projecting rearwardly from its side edges is a pair of cheek-plates *c*, in the upper ends of which are journaled the ends of a horizontal shaft *d*. Attached to this shaft *d* is an eccentric *e* 35 which is attached to a hand-lever *f*, whereby the eccentric will be supported by the shaft *d* and the eccentric may be rocked in the bearings in the cheek-plates.

Embracing the periphery of the cam or 40 eccentric is the rear end of a yoke *g* consisting of a steel rod bent upon itself, the two free ends of the yoke thus formed being slidingly mounted in tubular supporting guides *h* formed integral with the stationary 45 jaw *b* at one edge thereof. The free ends of the yoke-arms extend beyond the tubular guides *h* and carry the movable jaw *i* arranged in upright position and projecting laterally from the yoke-arms so as to be positioned at a point opposite the stationary 50 jaw and thus coöperate with the stationary jaw when the yoke-arms are drawn rearwardly. This movable jaw is attached to the yoke-arms by means of a pair of tubes *j* 55 formed integral with the jaw and through

which the yoke-arms pass, these tubular members *j* being sufficiently long to give the jaw a broad and substantial bearing or support upon the yoke-arms. The jaw *i* is adjustably mounted on the yoke-arms so as to 60 enable it to be positioned nearer to or farther from the stationary jaw to adapt the device for different sized nuts. As a means of providing for this adjustability of the movable jaw, I provide each yoke-arm with a 65 series of notches *k*, these notches being positioned so as to be engaged by the opposite edges of the plate *l* pivotally connected to the front face of the jaw *i* by pivot-screw *m*. It will be observed that by swinging 70 plate *l* upwardly by means of its handle *n*, the edges of the plate will be removed from the notches *k*, whereupon the movable jaw may be slid along the free ends of the yoke-arms and again locked in place by swinging 75 the plate downwardly.

As stated, the eccentric *e* lies within the bent end of the yoke, this eccentric being so positioned that when the lever *f* is swung downwardly the eccentric bears against the 80 connecting bar of the yoke and draws the yoke rearwardly, thereby drawing the movable jaw toward the stationary jaw. When the lever *f* is raised, the yoke and the movable jaw will be pushed forwardly by means 85 of plate *o*, whose bent ends *p* engage respectively one side of the eccentric and the rear side of the yoke, this plate being slotted at *q* for the passage of the shaft *d*. This plate *o* may be affixed to the yoke in any suitable 90 manner, preferably by raising one of the bent parts *p* to the connecting bar of the yoke. It will be observed that when the lever is raised, the eccentric will press against the adjacent lip *p* of the plate *o* 95 and thus, through the medium of the other bent end *p*, push the yoke forward.

The nature and scope of the invention having been thus indicated and its preferred embodiment having been specifically described, what is claimed as new is:

1. In a nut cracker, a support carrying a stationary jaw, a slideable yoke mounted in said jaw and carrying a companion jaw, an eccentric journaled in the rear of the stationary jaw and provided with an operating handle, and a plate connecting the yoke to the forward face of the eccentric. 105

2. The structure recited in claim 1, said plate being slotted for the passage of the 110

eccentric shaft and having bent ends engaging respectively one side of the eccentric and the rear end of the yoke.

3. In a nut cracker, a support carrying a stationary jaw, a yoke slidably mounted in said jaw and embodying a pair of parallel arms, means for sliding said yoke back and forth, a movable jaw adjustably mounted on the bars of the yoke, the means of adjustment consisting in notching the yoke arms and providing a pivoted plate on the movable jaw for engaging in said notches.

4. A nut cracker consisting of a support

provided with a stationary jaw, an eccentric and lever journaled on said stationary jaw, 15 a one-piece rod bent to form a yoke having a pair of parallel arms working in tubular bearings carried by said stationary jaw, the bent ends of the yoke being arranged to be connected by the eccentric, and a movable 20 jaw attached to the projecting ends of the yoke bars.

In testimony whereof I hereunto affix my signature.

CHARLES J. SCHIEMER.
